UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

CHAIN-SEVERING MECHANISM FOR SEWING-MACHINES.

1,170,349.

Specification of Letters Patent.

Patented Feb. 1, 1916.

Application filed January 6, 1910. Serial No. 536,766.

To all whom it may concern:

Be it known that I, DUDLEY S. SEYMOUR, a citizen of the United States, residing at Oak Park, in the county of Cook, State of Illinois, have invented certain new and useful Improvements in Chain-Severing Mechanism for Sewing-Machines, of which the following is a description, reference being had to the accompanying drawing and to the letters and figures of reference marked thereon.

My invention relates to an improvement in sewing machines, and while the invention has been especially devised by me for use in severing the chain of stitching between two consecutive bags on the filled bag sewing apparatus illustrated in application filed by C. McNeil, January 6th, 1910, Serial No. 536,669, nevertheless I do not desire to be thus limited in its application, as the invention is applicable to other uses than that thus specifically mentioned.

The herein described chain-severing mechanism, comprises a moving member and a stationary member, the former being operated from a feeding mechanism such as illustrated in my application for Letters Patent filed June 12th, 1909, Serial No. 501,817, and so far as the details of construction are concerned, the invention consists in the mechanism whereby the movable member of the severing device is connected to and operated from the feed dog-operating mechanism, illustrated in said application.

Looking at the invention from another standpoint, it embodies certain novel features of construction of the feed dog bars, whereby the chain to be severed is accurately guided to a plane on the opposite side of the feed dog from its feeding surface into the path of the moving member.

Finally, looking at the invention from the standpoint of its adaptability to a filled bag sewing apparatus, such as shown in application Serial No. 536,669, above referred to, the invention consists in the combination with a means for tilting the bag laterally after it has been sewed, of the severing device so located with respect thereto on the opposite side of the feed dog from the bag mouth, that the tilting of the bag will draw the chain taut, and into the space between the front and rear feed dog, where the cutter operates.

It will be seen that this particular chain-severing device contains several novel features in connection with its application to filled bag sewing apparatus; but, furthermore, as a severing device *per se* is applicable to a sewing machine, no matter to what use the latter may be put.

The invention, therefore, consists in the matters hereinafter described and referred to in the appended claims.

The invention is illustrated in the accompanying drawings, in which,

Figure 1 is an end view partly in section, of a portion of a sewing machine to which my invention is applied; Fig. 2 is a side view taken from the right of Fig. 1, the inclosing casing being removed; Fig. 3 is a detail view, showing the manner of securing the knife; Fig. 4 is a plan view of Fig. 1; Fig. 5 is a perspective view of a filled bag sewing apparatus, showing the application of my invention thereto, with the means for automatically drawing the chain of stitching into the path of the cutter; and Fig. 6 is a plan view of the throat plate and feed dogs.

In these drawings, 25 represents the front feed dog bar and 25' the two-part rear feed dog bar, between which two parts of the rear feed dog is left a space to allow the chain of stitching after the bag has been formed, to drop or be drawn between them, and into the open space A between the front and rear feed dogs, in which space the severing device operates.

B is the throat plate shown in plan in Fig. 6, and having openings a, a, for the passage of the feed dogs, and a contracted opening b between them beneath which opening the chain-severing device operates. It also has the needle opening c. Said feed dogs 25 and 25' are carried by the laterally extending arm 3^a of the feed dog supporting frame 26, which is pivoted at its front end to a rocking frame 27, which in turn is pivoted at 28 to a bracket 29, formed on the inner face of the cylindrical bed plate. The feed dog carrying frame 26 is pivoted near its front end to a link 31, by means of a pivot pin 32. The other end of the link 31 is connected by a pivot pin 33 to an arm 34, carried by the rock shaft 35, oscillated in the manner set forth in my application Serial No. 501,817, through the arm 34 and link 31, to raise and lower the front end of the

feed dog carrying frame 26. The forward and backward movements to the feed dog are given by the means set forth also in my aforesaid application. The arm 34 is extended to the rear, as shown at 34', and has a ball and socket or other free joint connection with the head C, which near its lower end has the socket connection for the ball d on the end of the stud e, which stud is formed on or secured to the rocking angular frame D, the horizontal arm f of which is sleeved or pivoted on a stud or shaft E, secured to a bracket F attached to the machine casing. The upwardly projecting arm G of the frame D is split to receive the knife member H of the severing device, this knife being adjustably clamped by the screw g. The oscillation of the rock shaft 35 swings the arm 34, and its part 34', thus through the ball joint connection to the head C, swinging the frame D on the shaft E, and reciprocating the knife member H, back and forth across the space between the forward and rear feed dogs beneath the throat plate. Coöperating with this reciprocating knife member is a stationary knife I, adjustably secured in a slot in the casing by the clamping screw h.

The reciprocating knife is held under tension of a spring i, around the shaft E, in a manner well known, to hold it laterally against the face of the stationary knife I, so that the proper shear cut will be made to sever the chain of stitching which has dropped or been drawn down between the two parts of the rear feed dog into the space between the two feed dogs, in which space the severing device operates.

The devices above described are designed especially for use in connection with an organized apparatus for conveying and sewing filled sacks, as illustrated in application for patent Serial Number 536,669, above referred to. Such an arrangement is shown in Fig. 5, in which the sewing machine M, containing all the mechanism previously described by me is set in the position therein shown, and overhangs a conveyer belt N which conveys the bags to the stitch-forming mechanism, and after they have been stitched, tilts them laterally automatically by means of the tilt board O, which is so arranged that as the bag tilts, it draws the chain of stitching taut, and into the path of movement of the cutting edge of the reciprocating knife member H, and severs the chain.

Having thus described my invention, what I claim as new and desire to secure by Letters Patent, is:—

1. A sewing machine including in combination, a throat plate, a feeding device, means for raising and lowering the feeding device including a rock shaft and for reciprocating the same, a chain-severing device in-

cluding a cutting member movable in a plane at right angles to the plane of the throat plate, and connections between said cutting member, and the rock shaft, whereby said cutting member is operated in unison with the raising and lowering of the feeding device.

2. In a sewing machine, in combination with a feeding device, a rock shaft for raising and lowering the feeding device, an arm 75 extending from said rock shaft, a pivoted cutting member, and a connection between the rock shaft and the pivoted cutting member for swinging the latter on its pivot in a plane crossing the line of feed. 80

3. A chain-severing device, comprising a cutting member arranged to operate in a plane crossing the line of feed, a pivoted frame to which the same is secured, a head having a free joint connection with the frame, and a rock shaft having an arm secured to it, said arm having a free joint connection with the head. 85

4. A sewing machine having a feeding device, with means for raising and lowering it, 90 in combination with a chain severing device including a cutting member, a pivoted frame to which the same is secured, a head having a free joint connection with the frame, and a rock shaft having an arm secured to it, 95 said arm having a free joint connection with the head, said rock shaft having also connections to the feeding device of a sewing machine, for raising and lowering said feeding device. 100

5. In a sewing machine, a rock shaft, an arm secured thereto having connections to the feeding device for raising and lowering the latter, said arm having an extension, a head freely pivoted thereto, a frame also 105 freely pivoted to said head, and pivoted also to a stationary part of the machine frame, and a cutting member secured to the frame.

6. In a sewing machine, a rock shaft, an arm secured thereto, having connections to the feeding device for raising and lowering the latter, said arm having an extension, a head freely pivoted thereto, a frame also freely pivoted to said head, and pivoted also to a stationary part of the machine frame, a cutting member secured to the frame, and a stationary cooperating member secured to the machine casing. 110

7. In combination with the feeding device including front and rear feed dogs, the latter having a recess between them, and the front and rear dogs being separated, a chain-severing device arranged to operate in the space between the front and rear dogs, the chain of stitching to be severed being deflected through the recess between the rear feed dogs.

8. In combination with the feeding device including front and rear feed dogs, the lat- 115

- ter having a recess between them, and the front and rear dogs being separated, a chain-severing device arranged to operate in the space between the front and rear dogs, the chain of stitching to be severed being deflected through the recess between the rear feed dogs, said chain-severing device being operated from the same mechanism which operates the feed dogs.
- 10 9. A feeding device, comprising front and rear feed dogs, separated from each other, the rear feed dogs being made in two parts with a longitudinal recess between to permit of the passage therethrough of the chain of stitching, and a chain-severing device operating in the space between the front and rear feed dogs.
- 15 10. An apparatus for sewing filled bags, comprising a sewing mechanism including a feeding device having separated front and rear feed dogs, the latter formed with a recess between them, a conveyer for the bags, and means for tilting the bags after the stitching has been performed, to draw the chain of stitching through the recess and into the space between the front and rear feed dogs, and a chain-severing device working in said space.
- 20 11. In a sewing machine, the combination of a needle, a feeding device, a throat plate having an opening for the feeding device and complementary stitch-forming mechanism, a severing device including relatively movable cutting members, said throat plate being provided with a longitudinal slot extending from said feed opening past said
- 25 cutting members, whereby the thread is guided to said cutting members.
12. In a sewing machine, a throat plate having openings for a plurality of feed dogs 40 arranged tandem, and also being provided with a longitudinal slot for connecting said openings, and a clipper acting on one side of said longitudinal slot.
13. In a sewing machine stitch-forming 45 mechanism including a needle, a feed dog having a portion in rear of the needle acting on the chain of thread, a second feed dog in rear of the first named feed dog, and being provided with a longitudinal groove, 50 whereby the chain of thread is guided and a chain-severing device for cutting the chain of thread.
14. In a filled bag sewing apparatus, 2 a sewing head and a conveyer, a clipper, said 55 sewing head having a two-part feeding device, the parts of which are located upon opposite sides of the clipper, one of said parts having a longitudinal groove.
15. In a filled bag sewing apparatus, a 60 sewing head and a conveyer, said sewing head being provided with a two-part feed and a throat plate, said throat plate having a slot connecting said feeds adapted to receive the chain of stitching. 65
- In testimony whereof I affix my signature in presence of two witnesses.
